UNITED STATES PATENT OFFICE.

EDWIN T. GREENFIELD, OF KIAMESHA, NEW YORK, ASSIGNOR TO GREENFIELD PAPER BOTTLE COMPANY, OF NEW YORK, N. Y., A CORPORATION OF NEW JERSEY.

MACHINE FOR MANUFACTURING PAPER BOTTLES OR CONTAINING VESSELS.

1,115,665.

Specification of Letters Patent.

Patented Nov. 3, 1914.

Original application filed December 14, 1908, Serial No. 467,372. Divided and this application filed June 1, 1911. Serial No. 630,625.

To all whom it may concern:

Be it known that I, EDWIN T. GREENFIELD, a citizen of the United States, and resident of Kiamesha, in the county of Sullivan and 5 State of New York, have made a new and useful Invention in Machines for Manufacturing Paper Bottles or Containing Vessels, of which the following is a specification.

My invention is directed to novel mechanism for manufacturing or constructing bottles or containing vessels for liquids generally, but particularly for dairy products, as milk, cream, etc., and it has for its object, to construct such a bottle or containing vessel 15 from fibrous material, such as paper, and in such manner as to produce a bottle or vessel of great strength, minimum lightness and at a minimum cost.

The machine constituting the subject matter of this application is especially designed to manufacture a bottle like that disclosed in U. S. Patent No. 940,810, granted to me on the 16th day of November, 1909, the same being made from a tube of paper and so 25 constructed that the throat and neck of the article possesses great strength thereby adapting it to be handled when being filled or transported from place to place as ordinary glass bottles are handled, but without 30 danger of damage or injury thereto.

For a full and clear understanding of the invention such as will enable others skilled in the art to construct and use the same, reference is had to the accompanying drawings, 35 in which,

Figure 1 is a part sectional, part side elevational view of a complete machine in the nature of a mold for constructing the before-mentioned bottle, illustrating also the 40 paper tube in position preparatory to performing the method of shaping the throat and neck of the bottle proper. Fig. 2 is a plan view as seen looking at Fig. 1 from the top toward the bottom of the drawings, upon 45 the assumption that the throat and neck forming parts have been forced into the position shown in dotted lines Fig. 1, the clamping ring shown in this figure not being seen in Fig. 1. Fig. 3 is a vertical sectional

view taken through Fig. 2 on the line X—X, 50 the two positions of the clamping ring and clamping wedges for use therewith being shown respectively in full lines and dotted lines. Fig. 4 is a perspective view of the double or duplex forming arms which successively effect the formation of the throat and neck proper of the bottle, and then the turning down of the folds of the surplus material so as to form ribs or plaits which give increased strength to those parts. Fig. 5 is a plan view of a beading tool for securing the bottom part thereof, a similar tool of smaller dimensions being provided for performing the like function with relation to the mouth ring at the upper end of the neck of the bottle; a sectional view of the body of the bottle being shown in position while the action of securing the bottom thereto is being effected. Fig. 6 is a sectional view taken through Fig. 5 and as seen 70 looking thereat from the bottom toward the top of the drawings in the direction of the arrows, but upon the assumption that the operating beading lever is removed to its outer or inoperative position; this view illustrating also the bottom of the bottle proper and the manner in which it is secured to the body thereof, together with the means for detachably securing it to a bench or table. Fig. 7 is a sectional view of the neck and 80 mouth of the completed bottle, illustrating the manner in which the mouth ring is secured to the neck proper by a beading tool like that shown in Figs. 5 and 6.

Referring now to the drawings in detail 85 and first to Figs. 1 to 4 inclusive, 1, 2 and 3 represent respectively the body part, the throat part and the neck part of an interior stationary forming mold having the conformation or shape of the interior of the 90 bottle to be constructed, said mold being two part in effect; that is to say, split in the direction of its length to a point approximating the neck thereof so that the same may be spread at its bottom. 4 represents 95 a tube made of paper or other fibrous material and having substantially the interior diameter of the exterior of the body part 1

of the mold. 5 represents the base or supporting part of the mold and 6 a wedge adapted to spread the bottom of the body part 1 thereof. 7, 7, represents a plurality 5 of forming arms which are provided at their bottoms with dowel pins 8, 8, adapted to fit loosely in radially disposed holes in the base 5, there being two of these dowel pins and corresponding holes for each arm. These 10 arms are of internal curvilinear cross section at the various parts of the length thereof to conform to the exterior curvilinear surface of the completed bottle. 9, 9, are curvilinear parts secured to the forming arm 7, 7, by screws, as shown, and the structural arrangement of all of these interconnected parts is such that when in closed position about the mold 1, 2 and 3, they fit snugly against the faces of all of the parts thereof, 15 as will be apparent on inspection of Figs. 1 and 2. 10, 10 constitute similar curvilinear forming arms designed to complete the folding down of the ribs or plaits after the first-named arms 7, 7 and the curvilinear parts 9, 20 9 have been drawn forward in the manner shown in Fig. 2. 11, 11 are pins pivotally securing the arms 10, 10 to the arms 7, 7, each pair of arms 7, 10, thus constituting in effect one set of duplex forming arms. 12 30 is a clamping ring designed to apply the proper pressure to the upper ends of the arms 7, 7, during the first step of the method and of the conformation of the bottle proper, and 13, 13 are wedges designed to 35 complete the final step of the forming method by forcing the curvilinear forming arms 10, 10 into their ultimate position, as will be described in connection with the mode of operation. 40 Referring now to Figs. 5 and 6, I will describe the apparatus for completing the bottle by securing the cup like bottom to the bottom of the body part of the bottle, and also for securing the mouth ring to the 45 upper end of the neck. 16 represents the base of a beading tool which is constructed of steel, iron or other metal, and 17, 17 are holes therethrough for detachably securing this tool to a bench or table through the 50 agency of pins 18, 18, 18. 19 represents a curvilinear bead forming part with a groove 20 in its exterior cylindrical surface, said bead forming part having the curvature on its exterior face of the inner surface of the 55 tube from which the bottle is to be constructed. 21 represents the male part of the bead forming tool having the same interior curvature as the groove 20 and secured directly to an operating lever 22, pivoted at 60 one end to the base 16 and provided with an operating handle 23 at the other end thereof. 24 represents a tubular cup which is constructed by forming the same in a heated die in a well known manner to those skilled

in the art of forming boxes and like articles 65 from paper under pressure in heated dies, said cup having the same exterior diameter as the inner diameter of the tube 4.

25 (see Fig. 7) represents the neck of the completed bottle as formed in the molds 70 above described, and 26 the mouth ring which is constructed by heated dies, in the same manner as was the cup 24, and is of such a nature that it may be slipped directly over the end of the neck so as to be secured 75 thereto by a concentric bead 27.

Having described the bottle proper and also the apparatus by which said bottle is constructed, I will now proceed to describe the method of operation of forming the 80 same. Referring first to Figs. 1 to 4 inclusive, all of the parts of the mold proper, which are seen in Figs. 1 and 4, are first subjected to heat in a furnace to such an extent as will not burn the paper when the 85 mold is being used. The interior mold is then inserted within the tube 4 until the bottom thereof is flush with the lower end of said tube and therefore becomes a stationary mold. The wedge 6 is then inserted in 90 the bottom of the interior mold and the parts as thus interconnected are dropped into the cylindrical opening in the bottom of the base or support 5, so that when the wedge 6 which now rests upon the bench or 95 table is forced forward to its limit, the tube will be firmly secured between the mold and the inner wall of said base. In this position the four arms 7, 7, 7, 7 and curvilinear parts 100 9, 9, 9, 9 are forced forward by the clamping ring 12, as will be apparent on inspection of Fig. 2, the ring 12 being driven down to its lowest position as seen in dotted lines Fig. 3. The parts are allowed to stand for an instant in this position until the paper sets 105 between the parts 9, 9, 9 and the interior mold.

The operation so far described performs the first step in the manufacture of my novel bottle hereinafter claimed, in that it molds 110 or forms that part of the tube lying respectively under the curvilinear parts 9, 9, 9, against the throat and neck parts of the interior forming mold, giving to the major portion of this end of the paper tube the 115 exact conformation or shape of well known types of bottles having cone-shaped throats and cylindrical necks. At the same time, however, it will be noted on examination of Fig. 2, there is a surplus of the paper which 120 is squeezed out between the lateral edges of the curvilinear parts 9, 9, 9 into the corresponding spaces between the pivoted arms 7, 7, 7. This surplus of material is in the nature of a plurality of folds, four such 125 being shown. The ring 12 is now removed and the arms 7, 7 released so that the lateral edges of the curvilinear parts 9, 9 are

released from behind the curved extensions of the paper seen in Fig. 2. The wedge 6 is now temporarily released so as to permit the bottle as thus far formed and its supporting mold to be rotated a fractional part of a revolution so as to bring the exterior of the curvilinear portions of the folds of the surplus material which are to constitute the plaits directly opposite the curvilinear parts 5 9, 9, 9, and the parts are again forced forward through the agency of the clamping ring 12 to their extreme limit, after which the arms 10, 10 are also forced forward to their extreme limit through the agency of 10 15 the wedges 13, 13 and the parts as thus are allowed to stand until all of the paper is set and the plaits have been sealed down, so to speak, against the faces of the throat and neck, said plaits being in effect of triangular 20 25 form. This part of the operation constitutes a further step in the manufacture of my novel bottle, in that it forms a plurality of box plaits with overlapping edges, which edges are parallel with each other throughout the entire length of the neck, and the continuation of such edges converge from the lower end of the neck to the lower end of the throat or the upper end of the body portion of the bottle proper. The ring 12 30 35 and wedges 13 are now removed and the wedge 6 withdrawn from the bottom of the interior mold when the body part thereof and neck of the bottle is in completed condition and ready for receiving the cup bottom and mouth ring to be applied thereto through the agency of the tool illustrated in Figs. 5 and 6, which operation will now be described. The tool illustrated in these figures of the drawings is first heated to approximately the same temperature as was the entire mold shown in Fig. 1 and it is 40 45 detachably secured to a bench or table through the agency of the pins 18, 18, extending through the holes 17, 17, 17 in the base thereof. The cup 24 is now inserted in the interior of the bottom of the bottle as thus far formed with the bottom part up, and with the inner side thereof resting against the curvilinear part 19 of the tool, with the 50 55 bottom proper of the bottle resting firmly on the top surface of the base 16. The operator then taking hold of the handle 23 of the lever 22 advances the heated male part 21 against the bottom of the bottle with sufficient force to form the concentric head, clearly illustrated in Fig. 6. The male part is then withdrawn and this operation repeated in sequence until a complete bead is formed around the bottom thereof which 60 65 effectually unites the same to the lower part of the body proper. This part of the operation constitutes a still further step in the completion of the bottle in the sealing or

securing of the bottom thereto. The mouth ring 26 is now slipped over the neck of the 65 bottle in the manner shown in Fig. 7 and a concentric head 27 is formed therearound in the same manner as the like head was formed around the bottom and with a like tool of smaller dimensions. 70

This operation just described constitutes the final step of the formation or shaping of the bottle and as thus formed it is subjected to a bath of molten paraffin or an equivalent water-proofing agent, which 75 effectually seals all of the parts together and renders the body and throat parts thereof practically transparent.

I do not limit my invention to the specific details of construction hereinbefore described and disclosed in the accompanying drawings for manufacturing bottles from paper or analogous fiber by forming the throat in plaits and securing the bottom and mouth ring thereto in the manner described, as a number of the features thereof might be materially departed from and still come within the scope of my claims hereinafter made. Nor do I claim in this application the method of making a bottle of 90 paper or analogous fibrous material as hereinbefore described, as this feature constitutes the subject matter of United States Patent No. 1,016,327 granted to me on the 6th day of February, 1912. 95

Having thus described my invention what I claim and desire to secure by Letters Patent of the United States—

1. A machine for making bottles or containing vessels embracing a mold having the conformation or shape of a bottle; in combination with two sets of compressible forming arms the inner surfaces of which conform in shape with the exterior surface of the neck and throat of the mold; together with means for holding all of said arms in relatively close relation to the mold, the first set of said arms forming the neck and throat of the bottle proper with intervening ribs or plaits, the other set completing the 110 operation, substantially as described. 100 105

2. A machine for making bottles or containing vessels embracing a two-part mold having the conformation or shape of a bottle, and a base for supporting said mold; in combination with means for spreading the mold at the bottom of the body part in frictional relation with the latter; together with a plurality of forming arms pivotally secured to the bottom and provided with means for holding the upper ends thereof around the neck part of the mold, substantially as described. 115 120

3. A machine for making bottles or containing vessels embracing a two-part mold; a base or support therefor, and means for 125

frictionally spreading the two parts of the
mold into frictional relation with the base;
together with forming arms the interior
surfaces of which have the conformation or
5 shape of the mold, and means for holding
said forming arms into frictional relation
with said mold, substantially as described.

In testimony whereof I have signed my
name to this specification in the presence of
two subscribing witnesses.

EDWIN T. GREENFIELD.
